US0D1048195S

(12) **United States Design Patent** (10) **Patent No.:** **US D1,048,195 S**
(45) **Date of Patent:** **** Oct. 22, 2024**

(54) **GAMING MACHINE**

(71) Applicant: **Aristocrat Technologies Australia Pty Limited**, North Ryde (AU)

(72) Inventor: **Ryan Priddy**, Franklin, TN (US)

(73) Assignee: **ARISTOCRAT TECHNOLOGIES AUSTRALIA PTY LIMITED**, North Ryde (AU)

(**) Term: **15 Years**

(21) Appl. No.: **29/728,535**

(22) Filed: **Mar. 19, 2020**

Related U.S. Application Data

(63) Continuation of application No. 29/632,471, filed on Jan. 8, 2018, now Pat. No. Des. 880,607.

(57) **CLAIM**

The ornamental design for a gaming machine, as shown and described.

DESCRIPTION

FIG. 1 is a front perspective view of a gaming machine showing my new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The broken lines shown in the display surface of the gaming machine in the drawings illustrate environment that forms no part of the claimed design. The remaining broken lines in the drawings illustrate portions of the gaming machine that form no part of the claimed design.

1 Claim, 6 Drawing Sheets
